UNITED STATES PATENT OFFICE.

ETHAN I. DODDS, OF PULLMAN, ILLINOIS, ASSIGNOR TO THE PULLMAN COMPANY, OF CHICAGO, ILLINOIS, A CORPORATION OF ILLINOIS.

BOLSTER CONSTRUCTION FOR CARS.

No. 831,652.

Specification of Letters Patent.

Patented Sept. 25, 1906.

Application filed August 23, 1905. Serial No. 275,378.

To all whom it may concern:

Be it known that I, ETHAN I. DODDS, a citizen of the United States, residing at Pullman, in the county of Cook and State of Illinois, have invented certain new and useful Improvements in Bolster Constructions for Cars, of which the following is a specification.

This invention relates to the construction of bolsters for cars, and although it is shown and described in connection with a car-body having a sloping floor or bottom and although it is especially adapted to such use obviously it may be employed in any type of car.

The invention involves several novel features, among which may be mentioned the use of an integral strut and combined spacer or fillet for the center sills in combination with one or more transverse tension-rods secured at their outer ends to angle-caps or anchors passing beneath the outer lower ends of the body-bolster and side sills and resting on the combined strut and spacer. These tension-rods in my structure replace the usual tension-plate and have the advantages over the latter that they can be quickly and easily removed or put in place as desired without cutting a single rivet, that they are cheaper than the customary plate, and that they are arranged to perform their function more advantageously, since they extend over a longer span than the tension-plates do. As an additional feature I provide a bellied plate extending longitudinally of the bolster, riveted to the above-mentioned strut and secured to the bottom of the car-body by means of rivets and an angle-bar running along its upper edge. This plate acts, as will be obvious to those skilled in the art, as a strut or support for the bottom of the car-body. Where such a strut is used in a car having a body with a sloping bottom, the angle-bar securing the same to the bottom has its flanges at an angle to correspond to the inclination of the body.

In the accompanying drawings, which form a part of the specification, I have illustrated one embodiment of my invention.

Figure 1 is a side elevation of a portion of a hopper-car embodying my invention. Fig. 2 is a longitudinal vertical section on the line 2 2 of Fig. 3, and Fig. 3 is a transverse section on the line 3 3 of Fig. 1.

The center sills comprise spaced channel-beams 10 10 with their flanges extending outwardly, the sills being held apart, yet joined together, by spacer 11, which includes a rectangular frame of the form shown in Fig. 3, the webs of the sills being riveted to the spacer. Integral with this spacer are outstanding flanges 12 12, overlapping the upper flanges 60 of the center sills, to which they are riveted, integral with which flanges are struts 13 13, having integral lugs 14 14, each pair of struts being spaced apart, as shown in Fig. 2. Body-bolster beams 15 are attached to the center 65 sills by means of angle-plates 16 and to the angle side sills 17 and side stakes 18 by angle-bars 19. Compression angle-bars 20 are riveted to the beams 15 on each side near their edges, and to their outstanding flanges is secured compression-plate 21, which passes beneath the lower flanges of the center sills. Instead of the usual tension-plate I employ one or more tension-rods 22, passing over and resting upon the upstanding struts 13 and 70 supporting at their outer ends the body-bolster beams and side sills. For this purpose I employ angular caps or anchors 23, each of which comprises a horizontal portion 25, extending beneath the body-bolster beam 80 and the flanges of the side sill, while the upright portion 24 overlaps the vertical flange of the side sill and extends on each side of the side stake 18, as shown in Fig. 1. Each angular cap or anchor 23 has the boss 26, 85 through which pass the ends of tension-rods 22, nuts on the ends of the rods holding the parts together, the rods resting on struts 13. On the accompanying drawings I have illustrated two such tension-rods; but it is apparent that any number of the same may be used, as conditions require. 90

As a support or strut for the sloping bottom of the hopper-car I provide the bellied plate 28, riveted to the spaced lugs 14 and secured at its outer ends to the side stakes by means of the angles 30. The inclined lower edges of this plate are supplied with integral compression-flanges 29, as is shown in Fig. 3. To connect this bellied plate, which constitutes a strut or support for the bottom of the car, to the latter, I provide angle-bar 32, which is riveted to the plate and also to the bottom of the car-body. I have shown and 95 100

described this portion of the invention as applied to a hopper-car with an inclined bottom; but it is obvious that the invention may be used in connection with car-bodies other than that shown and described.

Since the spacer, struts, and lugs are integral, it is evident that the underframe of the car, including the body-bolster, can be quickly assembled, owing to the small number of parts, and it will also be apparent that the tension-rods 22 may be readily put in place or removed by merely unscrewing the nuts at their outer ends, no cutting of rivets being required. It will also be obvious that my improved means for supporting the car-body above the body-bolster involves a very simple construction, which nevertheless provides sufficient strength with a minimum of weight. Instead of making plates 15 and 28 integral, as has been usual, I make the latter bellied in shape and separate from the bolster-beams, in this way saving somewhat in the weight of the parts and at the same time constructing plate 28 of a shape to effectually withstand the load or strain put upon it.

Obvious and minor mechanical changes which will suggest themselves to those skilled in the art will fall within the substance of my invention as defined in the appended claims.

This patent is intended to embrace only so much of the disclosure made herein as is covered by the claims.

I claim—

1. In a car-frame, the combination of spaced center sills, an integral strut and spacer for said sills, body-bolster beams secured to said sills, a tension rod or rods resting on said strut, and anchors under the outer ends of said bolster-beams fastened to the ends of the tension rod or rods, substantially as described.

2. In a railway-car, the combination of a car-body spaced center sills, a spacer for said sills, and a car-body-supporting plate fastened to said spacer and to said car-body, substantially as described.

3. In a railway-car, the combination of spaced center sills, a spacer for said sills, a bellied supporting-plate fastened to said spacer, and an angle-bar securing said plate to the bottom of the car-body, substantially as described

4. In a railway-car, the combination of spaced center sills, a spacer for said sills having a lug, and a supporting-plate fastened to said lug and to the body of the car, substantially as described.

5. In a railway-car, the combination of spaced center sills, a spacer for said sills having a lug and a strut, body-bolster beams fastened to said sills, a tension-rod resting on said strut and supporting the outer ends of said body-bolster beams and a supporting-plate riveted to said lug and fastened to the body of the car, substantially as described.

6. In a railway-car, the combination of spaced center sills, a spacer for said sills having a lug and a strut integral with said spacer, body-bolster beams fastened to said sills, a tension-rod resting on said strut, supporting-anchors at the ends of said bolster-beams secured to the ends of said tension-rod, a bellied supporting-plate riveted to said lug, and an angle-bar securing said plate to the bottom of the car-body, substantially as described.

7. In a railway-car, the combination of a car-body, spaced center sills, body-bolster beams secured thereto, a spacer for said sills disposed between the same, a pair of spaced struts supported by said center-sill spacer, twin tension-rods resting on said pair of struts and sustaining the outer ends of said bolster-beams, a pair of spaced lugs one on each of said struts, and a car-body-supporting plate between and riveted to said lugs, substantially as described.

8. In a railway-car, the combination of a car-body, spaced center sills, body-bolster beams secured thereto, a spacer for said sills disposed between the same, a pair of spaced struts integral with said center-sill spacer, twin tension-rods resting on said pair of struts and sustaining the outer ends of said bolster-beams, a pair of spaced lugs one integral with each of said struts, a bellied car-body-supporting plate between and riveted to said lugs, and an angle-bar connecting said plate and said car-body, substantially as described.

ETHAN I. DODDS.
